US00D835620S

(12) **United States Design Patent** (10) **Patent No.:** **US D835,620 S**
(45) **Date of Patent:** **** Dec. 11, 2018**

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/592,182**

(22) Filed: **Jan. 27, 2017**

Related U.S. Application Data

(63) Continuation of application No. 29/542,300, filed on Oct. 13, 2015, which is a continuation of application (Continued)

(57) **CLAIM**

The ornamental design for an electronic device, as shown and described.

DESCRIPTION

FIG. 1 is a bottom front perspective view of an electronic device showing the claimed design;

FIG. 2 is a bottom rear perspective view thereof;

FIG. 3 is a top front perspective view thereof;

FIG. 4 is a top rear perspective view thereof;

FIG. 5 is a front view thereof;

FIG. 6 is a rear view thereof;

(Continued)

FIG. 7 is a top view thereof;
 FIG. 8 is a bottom view thereof;
 FIG. 9 is a left side view thereof; and,
 FIG. 10 is a right side view thereof.
 The shade lines in the Figures show contour and not surface
 ornamentation.
 The dashed broken lines in the figures show portions of the
 electronic device that form no part of the claimed design.

1 Claim, 8 Drawing Sheets

Related U.S. Application Data

No. 29/457,962, filed on Jun. 14, 2013, now Pat. No. Des. 749,563, which is a continuation of application No. 29/431,553, filed on Sep. 7, 2012, now Pat. No. Des. 684,571, application No. 29/592,182, which is a continuation of application No. 29/586,519, filed on Dec. 5, 2016, which is a continuation of application No. 29/493,571, filed on Jun. 11, 2014, now Pat. No. Des. 773,453, which is a continuation of application No. 29/423,180, filed on May 29, 2012, now Pat. No. Des. 707,223.
